POCKET ADDING DEVICE

Florindo J. Perillo, Tucson, Ariz.

Application May 31, 1950, Serial No. 165,316

3 Claims. (Cl. 235—78)

1

This invention relates to pocket adding devices. The object of the invention is to provide a device which can be conveniently carried and used by a shopper in self-service stores such as supermarkets, and will enable the shopper to add up the total cost of his purchases as he selects them. Therefore, by using the invention, the shopper may easily keep track of the total amount which he is spending, and will arrive at the checking, paying and parcelling counter with knowledge of the total cost of the goods which he desires to purchase, thus guarding against over-charging.

The invention will be understood from the following description of a preferred embodiment thereof, taken in connection with the accompanying drawing, in which Fig. 1 is a bottom view of the device; Fig. 2 is a top view thereof; Fig. 3 is a sectional elevation through the device on the plane 3—3 of Fig. 2; Fig. 4 is a top view of the device, partly in section and with some of the parts broken away; Fig. 5 is a fragmentary view of the bottom side of the penny-dial; Fig. 6 is a fragmentary view of the top side of the penny-dial; Fig. 7 is a bottom view of the cover-plate; Fig. 8 is a back view of the dollar-dial; and Fig. 9 is a perspective view of the detents by which the penny-dial and the cover-plate are retained in any of the positions to which each of them may be manually rotated.

Referring to the drawing, the convenient form of the device will be apparent from Figs. 1 and 2 from which it will be evident that the various parts are arranged within a dish-shaped housing having a bottom 10, a circular side wall 12, and a lug 14 providing an opening adapted to receive a strap (not shown) by which the device may be suspended.

As shown in Fig. 1, the bottom 10 of the housing is provided with a window 16 through which dollar figures are visible, and a window 18 through which cents figures are visible, as hereinafter described. However, of course a single window, in place of the windows 16 and 18 may be provided. The housing may be made of any suitable material, such as a plastic or metal. Arranged for manual rotation in the housing, is a penny-dial 20 which, as shown in Fig. 3, is provided in its bottom side with an annular cavity 22; and on both sides bears figures from 0 to 99 which are preferably radially arranged as shown in Figs. 4, 5 and 6. The figures on the bottom side of the penny-dial 20 are located so as to be individually visible through the window 18 in the bottom 10 of the housing as said penny-dial 20 is rotated, as will be evident from Figs. 1 and 4.

Rotatably mounted on a stud 24 upwardly extending from the bottom 10 of the housing, is a dollar-dial 26 which (as shown in Fig. 8) is provided on its bottom side with radially arranged figures from 0 to 9 which are located so as to be individually visible through the window 16 in the bottom 10 of the housing as said dollar-dial 26

2

rotates, as shown in Fig. 1. As is best shown in Figs. 4 and 8, the hub portion 28 of the penny-dial 20 is provided with a lug 30 which cooperates with ten notches 32 in the edge of the dollar-dial 26, thereby causing the dollar-dial 26 to rotate one-tenth of a revolution for each complete revolution of the penny-dial 20. It will be noticed that the edge portions of the dollar-dial 26 between the notches 32 are so shaped that they conform to the cylindrical surface of the hub 28 of the penny-dial 20, thereby preventing the dollar-dial 26 from movement except by the engagement of the lug 30 with the notches 32.

A cover-plate 34 is arranged so as to be manually rotatable in said housing outside of the penny-dial 20 and on the hub portion 28 of the latter, as will be apparent from Fig. 3. In order to reduce the friction between the cover-plate 34 and the penny-dial 20, a circular ridge 36 is provided on the bottom side of the cover-plate 34; but of course this ridge might be provided on the top side of the penny-dial 20. As shown in Figs. 2 and 3, the cover-plate 34 is provided with a window 38 through which the figures on the top side 25 of the penny-dial 20 are visible as said penny-dial 20 is rotated.

As will be obvious from Fig. 3, the bottom 10 of the housing and the penny-dial 20 are provided with central circular holes adapted to receive a rivet 40. The cover-plate 34 is retained in co-operative relation to the penny-dial 20 by means of a disk 42 having a diameter such that its edge extends a short distance over the surface of the cover-plate 34 (as shown in Fig. 3), and this disk 35 42 is provided with a central hole through which the rivet 40 passes. Since the rivet 40 is provided at one end with a head 44 and at the opposite end is shouldered and carries a washer 46, it will be evident that after the riveting has been accomplished the rivet 40 will retain the penny-dial 20 and the cover-plate 34 in rotatable relation to the housing and to one another. As best shown in Fig. 2, the cover-plate 34 is provided with knobs 47 and 48; and the penny-dial is provided with knobs 49 and 50 which project through openings in the disk 42. These knobs 47—48 and 49—50 facilitate manual rotation of the cover-plate 34 and the penny-dial 20.

As will be evident from the drawing, the penny-dial 20 and the cover-plate 34 are retained in any one of the positions to which each of them may be manually rotated, by detents 51 and 52 which extend in opposite directions from a central portion 53 (as shown in Fig. 9) 55 and cooperate with the notched edges of the penny-dial 20 and cover-plate 34, as is best shown in Fig. 4. The central portion 53 of the detents 51 and 52 is provided with a hole 54 adapted to receive a screw or rivet 55 by which the central portion 53 of the detents is secured to the inside of the side wall 12 of the housing. There are 100 equally-spaced notches in the edge of the cover-plate 34, one of these notches being in

line with the window 38; and there are 100 equally-spaced notches in the edge of the penny-dial 20, and the valleys of these notches are opposite the figures on the penny-dial.

The manner in which the device is used will now be described. First, the user makes sure (by manipulation if necessary) that the penny-dial 20 and the dollar-dial 25 are at their 0 positions, as indicated in Fig. 1, and that the cover-plate 34 is in the position shown in Fig. 2 in which the zeros are visible through the window 38. Then the user utilizes the knobs 49 and 50 to rotate the penny-dial 20 in the direction of the arrow which is followed by the plus (+) signs, until the figure representing the cost in cents of the first article which he desires to purchase is visible through the window 38 in the cover-plate 34. The user then rotates the cover-plate 34, by means of the knobs 47—48 (in either direction) until the zeros on the top side of the penny-dial 20 are again visible through the window 38. Such rotations of the penny-dial 20 and the cover-plate 34 are repeated for each article which the user desires to purchase. When the user has completed his selection of the articles which he desires to purchase, and the price of each of them has been recorded as just explained, the user will find that the total amount (up to \$9.99) will be indicated by the figures which are visible through the windows 16 and 18 in the bottom 10 of the housing. Thus the device enables a shopper to total-up the cost of the various articles which he desires to purchase, thereby enabling him to keep track of the amount which he is spending, and making it possible for him to check the accuracy of the total arrived at by the cashier of the store when the purchases are paid for.

Of course, in the event that the user of the adding device records in it the price of an article which he later decides not to purchase, he can deduct the price of that article by rotating the cover plate 34 in either direction until the amount to be deducted is visible through the window 38. After which he rotates the penny dial 20 in the direction indicated by the arrow followed by minus (—) signs, until the zeros are visible through the window 38. Then, if he so desires, he may proceed with recording in the device the cost of articles which he may subsequently decide to purchase.

What is claimed is:

1. A pocket adding device having a housing provided with a window or windows, a penny-dial manually rotatable in said housing, said penny-dial being provided on both sides with circularly arranged figures from 0 to 99, the figures on the bottom side of said penny-dial being located so as to be individually visible through the window in said housing as said penny-dial is rotated, a dollar-dial rotatably mounted in said housing between said penny-dial and the bottom of said housing, means cooperating with said penny-dial and with said dollar-dial for causing said dollar-dial to rotate one-tenth of a revolution for each complete revolution of said penny-dial, said dollar-dial being provided on its bottom side with circularly arranged figures from 0 to 9 which are located so as to be

individually visible through the window in said housing as said dollar-dial rotates, a cover-plate manually rotatable in said housing outside of said penny-dial and provided with a window through which the figures on the top side of said penny-dial are individually visible as said penny-dial is rotated, and means for retaining said penny-dial and said cover-plate in any of the positions to which each of them may be manually rotated.

- 5 2. A pocket adding device having a dish-shaped housing provided in its bottom with a window or windows, a penny-dial manually rotatable in said housing, said penny-dial being provided in its bottom side with an annular cavity and near its outer edge on both sides with circularly arranged figures from 0 to 99, the figures on the bottom side of said penny-dial being located so as to be individually visible through the window 15 in said housing as said penny-dial is rotated, a dollar-dial rotatably mounted in said housing in the said annular cavity between said penny-dial and the bottom of said housing, means cooperating with said penny-dial and with said dollar-dial for causing said dollar-dial to rotate one-tenth of a revolution for each complete revolution of said penny-dial, said dollar dial being provided on its bottom side with circularly arranged figures from 0 to 9 which are located so 20 as to be individually visible through the window 20 in said housing as said dollar-dial rotates, a cover-plate manually rotatable in said housing outside of said penny-dial and provided with a window through which the figures on the top 25 side of said penny-dial are individually visible as said penny-dial is rotated, and means for retaining said penny-dial and said cover-plate in any of the positions to which each of them may be manually rotated.
- 30 3. A pocket adding device having a dish-shaped housing provided in its bottom with an upwardly extending stud and with a window or windows, a penny-dial having a hub and manually rotatable in said housing, said penny-dial being provided in its bottom side with an annular cavity and near its outer edge on both sides with circularly arranged figures from 0 to 99 and on its edge with 100 notches, the figures on the bottom of said penny-dial being located so as to be individually visible through the window in said 35 housing as said penny-dial is rotated, a dollar-dial rotatably mounted in said housing on said stud and in said annular cavity between said penny-dial and the bottom of said housing, means cooperating with said hub of the penny-dial and with said dollar-dial for causing said dollar-dial to rotate one-tenth of a revolution for each complete revolution of said penny-dial, said dollar-dial being provided on its bottom side with radially arranged figures from 0 to 9 which are located so as to be individually visible through the window in said housing as said dollar-dial rotates, a cover-plate having in its edge 100 notches and manually rotatable in said housing outside and on said hub of said penny-dial and 40 provided with a window through which the figures on the top side of said dial are individually visible as said penny-dial is rotated, and detents supported on said housing and cooperating with the notches in the edges of said penny-dial and cover-plate for retaining them in any of the positions to which each of them may be manually rotated.
- 45 4. A pocket adding device having a dish-shaped housing provided in its bottom with an upwardly extending stud and with a window or windows, a penny-dial having a hub and manually rotatable in said housing, said penny-dial being provided in its bottom side with an annular cavity and near its outer edge on both sides with circularly arranged figures from 0 to 99 and on its edge with 100 notches, the figures on the bottom of said penny-dial being located so as to be individually visible through the window in said housing as said penny-dial is rotated, a dollar-dial rotatably mounted in said housing on said stud and in said annular cavity between said penny-dial and the bottom of said housing, means 50 cooperating with said hub of the penny-dial and with said dollar-dial for causing said dollar-dial to rotate one-tenth of a revolution for each complete revolution of said penny-dial, said dollar-dial being provided on its bottom side with radially arranged figures from 0 to 9 which are located so as to be individually visible through the window in said housing as said dollar-dial rotates, a cover-plate having in its edge 100 notches and manually rotatable in said housing outside and on said hub of said penny-dial and provided with a window through which the figures on the top side of said dial are individually visible as said penny-dial is rotated, and detents supported on said housing and cooperating with the notches in the edges of said penny-dial and cover-plate for retaining them in any of the positions to which each of them may be manually rotated.
- 55 5. A pocket adding device having a dish-shaped housing provided in its bottom with an upwardly extending stud and with a window or windows, a penny-dial having a hub and manually rotatable in said housing, said penny-dial being provided in its bottom side with an annular cavity and near its outer edge on both sides with circularly arranged figures from 0 to 99 and on its edge with 100 notches, the figures on the bottom of said penny-dial being located so as to be individually visible through the window in said housing as said penny-dial is rotated, a dollar-dial rotatably mounted in said housing on said stud and in said annular cavity between said penny-dial and the bottom of said housing, means 60 cooperating with said hub of the penny-dial and with said dollar-dial for causing said dollar-dial to rotate one-tenth of a revolution for each complete revolution of said penny-dial, said dollar-dial being provided on its bottom side with radially arranged figures from 0 to 9 which are located so as to be individually visible through the window in said housing as said dollar-dial rotates, a cover-plate having in its edge 100 notches and manually rotatable in said housing outside and on said hub of said penny-dial and provided with a window through which the figures on the top side of said dial are individually visible as said penny-dial is rotated, and detents supported on said housing and cooperating with the notches in the edges of said penny-dial and cover-plate for retaining them in any of the positions to which each of them may be manually rotated.
- 65 6. A pocket adding device having a dish-shaped housing provided in its bottom with an upwardly extending stud and with a window or windows, a penny-dial having a hub and manually rotatable in said housing, said penny-dial being provided in its bottom side with an annular cavity and near its outer edge on both sides with circularly arranged figures from 0 to 99 and on its edge with 100 notches, the figures on the bottom of said penny-dial being located so as to be individually visible through the window in said housing as said penny-dial is rotated, a dollar-dial rotatably mounted in said housing on said stud and in said annular cavity between said penny-dial and the bottom of said housing, means 70 cooperating with said hub of the penny-dial and with said dollar-dial for causing said dollar-dial to rotate one-tenth of a revolution for each complete revolution of said penny-dial, said dollar-dial being provided on its bottom side with radially arranged figures from 0 to 9 which are located so as to be individually visible through the window in said housing as said dollar-dial rotates, a cover-plate having in its edge 100 notches and manually rotatable in said housing outside and on said hub of said penny-dial and provided with a window through which the figures on the top side of said dial are individually visible as said penny-dial is rotated, and detents supported on said housing and cooperating with the notches in the edges of said penny-dial and cover-plate for retaining them in any of the positions to which each of them may be manually rotated.
